CLAIM

I claim the ornamental design for a swimming assistance apparatus, as shown and described.

DESCRIPTION

FIG. 1 is a perspective view of a swimming assistance apparatus showing the new design;
FIG. 2 is a front view thereof;
FIG. 3 is a rear view thereof;
FIG. 4 is a left side view thereof;
FIG. 5 is a right side view thereof;
FIG. 6 is a top plan view thereof; and,
FIG. 7 is a bottom plan view thereof.
